UNITED STATES PATENT OFFICE

THEODORE NELSON BISHOP, OF PITTSBURGH, PENNSYLVANIA.

HANGER FOR DRYING CLOTHES AND THE LIKE.

1,185,167.

Specification of Letters Patent. Patented May 30, 1916.

Application filed May 10, 1915. Serial No. 27,094.

To all whom it may concern:

Be it known that I, THEODORE NELSON BISHOP, a citizen of the United States, residing at Pittsburgh, in the county of Allegheny and State of Pennsylvania, have invented certain new and useful Improvements in Hangers for Drying Clothes and the like, of which the following is a specification.

10 This invention relates to hangers for drying clothes and more particularly to that type which is attached to the ceiling and walls of a room and which may be readily adjusted to elevate the clothes out of the 15 way of the occupants of the room.

The primary object of the invention resides in the provision of means, whereby the drying frames or bars may be operated, so that the same are maintained on an even plane.

20 A further object of the invention is to provide a drying apparatus which may be easily operated, inexpensive to manufacture and readily adjusted to several positions and it consists of the features, combinations 25 and details of construction hereinafter described and claimed.

Referring to the accompanying drawing, which forms a part of the specification, Figure 1, is a perspective view of my improved 30 hanger attached to the supporting ceiling and wall blocks. Fig. 2, is a detail view of a cross bar, showing its connection with the longitudinal hanger rail, the latter being broken away.

35 Heretofore, the main objection encountered in hangers of this particular type, is that the same occupied too much space on the floor, requiring the folding of the hangers when not in use, and I have overcome 40 this objection by suspending the hanger from the ceiling, which I do by means of a series of pulleys 1, screwed into the ceiling blocks 2, which latter are appropriately secured by screws or other means, to the ceiling 45 at the opposite ends of the room. These ceiling blocks 2, may be constructed of wood or metal, and in fact the entire apparatus may be of like construction.

The hanger proper consists of a longitudinal rail 3, supported on, and detachably connected adjacent its ends, to the cross-bars 4 and 5, which latter, are formed with recesses 6, at their central portion for the reception of the rail. The said rail adjacent 55 its ends is likewise recessed at 7, so that a perfect connection of the rail and bars is

assured. Screws 8, may be employed to hold the rail and bar elements together. The rail 3, may be of any desired length, and if necessary extend the entire length of the room, whereby a maximum clothes-hanging capacity is assured.

The rail 3, and the cross-bars 4 and 5, are suspended from the ceiling blocks 2, by means of ropes, which pass over the pulleys 1, as hereinafter will be more fully described.

The pulleys 1, are mounted in the ceiling blocks 2, in series of two and three, on the opposite sides of the room, and the main 70 rope 9, passes over the central of the three pulleys, across the room and over the rear pulley of the series of two pulleys, to the rear part of the cross-bar 5. Both cross-bars 4 and 5, are apertured at 10, adjacent 75 their ends for the reception of the rope ends, which are suitably knotted to prevent the withdrawal of the rope therefrom, and by which means they are supported.

Connected to the main rope 9, at 11, are 80 the ropes 12, which pass over the front and rear pulleys 1, and are likewise secured to the cross-bar 4, adjacent the ends thereof.

The rope 13, is secured at 14, to the rope 9, and passes over the front pulley 1, at the 85 opposite end of the room, to the cross-bar 5, being secured thereto by knotting the end thereof. It will thus be seen that the frame is evenly supported at their ends, so that the device is equally balanced.

90 The cross-bar 4, is provided with apertures 14^a, at its opposite ends, through which pass the ropes 15 and 16, the latter being knotted at their ends, serving to hold the same therein. The ends of the cross-bar 5, 95 are channeled to form the wedge-shaped grooves 15^a, and the ropes 15 and 16, are stretched in alinement with the rail 3, and have their ends inserted in the grooves 15^a, knots being made for holding the ropes 100 therein, the wedge-shaped opening of the slots 15^a, permitting the gripping of the said ropes at this point.

A bar 17, is attached in any suitable manner by nails or screws 18, to the wall and 105 carries the retaining block 19, and the main rope 9, is knotted at several places and inserted between one of the jaws of the retaining blocks 19, whereby the hanger frame is held in adjusted position.

110 To elevate the hanger frame it is only necessary to pull down on the main rope 9,

and insert the same in the retaining block, the proper knot thereon, holding the hanger frame in position. To lower the frame the aforesaid operation is reversed.

5 In operation the hanger frame is lowered and the clothes hung from the cross-rods and the ropes 15 and 16, the main rope 9, being pulled down, resulting in the elevation of the hanger frame toward the ceiling, so that the same is out of the way.

10 The device is at all times out of the way of the occupants of the room and does away with the clothes horse, which occupies so much space.

15 It is understood that changes, variations and modifications may be resorted to which come within the scope of the claim hereunto appended.

Having fully described my invention, 20 what I desire to claim as new and secure by Letters Patent is:

Copies of this patent may be obtained for five cents each, by addressing the "Commissioner of Patents, Washington, D. C."

In a clothes drier, the combination with a drier frame composed of recessed cross-bars, a detachable connecting rail recessed adjacent its ends fitting in the recesses of 25 the cross-bars, clothes lines connecting the cross-bars, pulleys in series of two and three designed to be suspended from a ceiling, a main hoisting rope passing over the central of the series of three pulleys having end 30 branches passing over series of two pulleys and secured to the cross-bar adjacent its ends, rope branches attached to main hoisting rope passing over the front and rear of the series of three pulleys and secured to the 35 cross-bar adjacent its ends, as set forth.

In testimony whereof I affix my signature in presence of two witnesses.

THEODORE NELSON BISHOP.
